DESIGN FOR A COMBINED HOOD AND SUPPORTING BASE FOR A DICTATING MACHINE

William J. O'Neil, Atlantic Beach, and Leland Stanford Briggs, New York, N. Y., assignors to Dictaphone Corporation, New York, N. Y., a corporation of New York

Application November 26, 1940, Serial No. 96,824

Term of patent 14 years

To all whom it may concern:

Be it known that we, William J. O'Neil and Leland Stanford Briggs, both citizens of the United States and residents, respectively, of Atlantic Beach, in the county of Nassau and State of New York, and of New York, in the county of New York and State of New York, have invented a new, original, and ornamental Design for a Combined Hood and Supporting Base for a Dictating Machine, of which the following is the specification, reference being had to the accompanying drawing forming part thereof.

and front of a combined hood and supporting base for a dictating machine, showing our new design.

The dominant features of our design reside in the portions shown in full lines.

We claim:

The ornamental design for a combined hood and supporting base for a dictating machine, substantially as shown and described.

WILLIAM J. O'NEIL.
LELAND STANFORD BRIGGS.
